UNITED STATES PATENT OFFICE

2,399,998

INTERNAL-COMBUSTION ENGINE

Charles I. Fox, Pella, Iowa

Application October 5, 1943, Serial No. 504,987

15 Claims.

(Cl. 123—14)

This invention relates to an internal combustion engine having a rotating power or lever wheel for imparting rotation to the main shaft of the engine.

One object of the invention is to provide an engine of this general character having a rotor within a stator, a shuttle valve including an abutment bar movable into the stator, the movement thereof being controlled by compressed air mechanism and a check arm and link device which locks the abutment bar against movement until the pressure of the air has been built up to a point sufficiently high to properly operate it.

Another object is to provide an engine having associated with the shuttle valve and rotor, a fuel control unit of novel character, including an air valve for relieving pressure therefrom, a second valve for admitting fuel under pressure, and a third valve for admitting air under high pressure to form a fuel mixture, the fuel mixture being discharged into an expansible chamber of the engine and exploded therein.

A further object is to provide an air compressor unit operating in conjunction with the fuel control unit for compressing a charge of air in the expansible chamber so that the air is relatively hot, so that when the fuel is discharged into it, explosion will be effected for operating the engine.

Still another object is to provide an engine having a combustion control unit comprising a first piston and a second piston telescopically related to each other and operated by compressed air, the pressure of expansion, and a check arm and link mechanism, all three in conjunction with each other to control the explosion and obtain maximum power therefrom.

Further objects are to provide a lubricating oil system in connection with the engine and a simple connection between the various operating units in the form of cranks and connecting rods.

With these and other objects in view, my invention consists in the construction, arrangement and combination of the various parts of my device whereby the objects contemplated are attained, as hereinafter more fully set forth, pointed out in my claims and illustrated in the accompanying drawings, in which:

Figure 1 is a plan view of the left half of the engine cut at the center line of the main shaft, with a portion of a fuel control unit and a compressor unit shown in section.

Figure 2 is a sectional view on the line 2—2 of Figure 1.

Figure 1A is a plan view of the right half of the engine, also cut at the center line, this figure

being a continuation of Figure 1 with a portion of the power cylinders for a shuttle valve shown and sectioned with an explosion control unit shown in section.

5 Figure 3 is a vertical sectional view through the engine on the line 3—3 of Figure 1, showing only the left half.

Figures 4, 5 and 6 are diagrammatic views showing various positions of the rotor during 10 operation.

Figure 3A is a vertical sectional view on the line 3A—3A of Figure 1A, this figure being a continuation of Figure 3.

15 Figure 7 is a sectional view similar to Figure 3A showing the parts in a different position.

Figure 8 is a vertical sectional view on the line 8—8 of Figure 3.

Figure 9 is a sectional view on the line 9—9 of Figure 8 showing the shuttle valve mechanism.

20 Figure 10 is a similar sectional view showing the shuttle valve in a different position, and:

Figure 11 is a view similar to Figure 7 showing the parts in still a different position.

25 On the accompanying drawings I have used the reference character F to indicate a frame. The frame F is box-like in character so as to form an oil sump in which a supply of lubricating oil may be contained. The frame F at its center has a pair of stators indicated generally at S in which 30 rotors R are rotatably mounted.

Each rotor R consists of a disc having a notch therein, the bottom of which is indicated at 10 and the ends of which are indicated at 12 and 14.

35 The rotors R are rigidly secured to a main shaft 18. The shaft 18 as shown in Figure 8 is journaled in bearings 20 and end plates 22. The bearings 20 are removably mounted in the stators S and the center of the main shaft is journaled in a bearing 24 removably positioned with respect 40 to a partition 25 of the frame F so that the entire main shaft may be removed or inserted lengthwise with relation to the frame F and the stators S.

The main shaft 18 has two pairs of crank pins 45 26 and 28 carried thereby, and the bearings 20 and 24 are made large enough to accommodate the crank arms therefor. Connecting rods 27 and 29 are journaled on the crank pins 26 and 28 respectively, and extend in opposite directions from the main shaft 18. The connecting rods 27 extend to crank pins 30 of a cam shaft 32 while the connecting rods 29 extend to crank pins 34 of a crankshaft 36.

The cam shaft 32 is journaled in five bearings 50 38 of the frame F and the crankshaft 36 is jour-

nalled in a center bearing 40 and two other bearings 42 of the frame F (see Figures 1A and 3A respectively). The crank pins 26 are set at 90° to each other and so are the crank pins 28, the crank pins 30 and 34 being similarly set so that the cam shaft 32 and the crankshaft 36 rotate simultaneously and in unison with the main shaft 18. This provides a comparatively simple power transmission means without the necessity of gearing, chains or the like.

Cooperating with the notch ends 12 and 14 of the rotor R (which are helically inclined as shown in Figures 9 and 10) is a shuttle valve including an abutment bar 44. The abutment bar slides in a housing provided therefor in the frame F and sliding motion is imparted thereto by shuttle valve pistons P. The pistons P reciprocate in shuttle valve cylinders 48 of the frame F and are connected as by extensions 50 with the abutment bar 44.

For effecting movement of the pistons P in the cylinders 48 I provide power cylinders 52 having therein power pistons P' which are operated by connecting rods 46 from crank pins 54 of the crankshaft 36.

Instead of receiving air at atmospheric pressure, the power cylinders 52 receive air from supply pipes 56 which supply air at a high pressure—for instance 250 pounds per square inch. The supply pipes 56 communicate with inlet ports 58 in the walls of the cylinders 52. The air thus introduced into the cylinders is further compressed by the power pistons P' and exhausted through outlet ports 60 into the shuttle valve cylinder 48 as will hereinafter appear.

A means is provided for stopping and locking the shuttle valve in its opposite positions consisting of a pair of check arms 62 pivoted on a stationary stud 64 anchored relative to the frame F. Links 66 connect the outer ends of the arms 62 to studs 68 carried by the abutment bar.

The joints between the links and arms are indicated generally at 70 and these joints are adapted to coact with seats 72 formed in trigger elements 74 (see Figure 8). The trigger elements 74 have extensions 76 and 78 slidable in perforated ears 80 and 82 of the frame F, and are biased in one direction by springs 84. Secured to the main shaft 18 adjacent the center thereof is a pair of trip arms 86 for coacting with the extensions 76 for actuating the trigger elements 74 as will hereinafter appear. Each trip arm 86 is provided with an inclined cam surface 87 for this purpose as shown in Figure 9.

Leading from the shuttle valve cylinders 48 are exhaust passageways 88, each of which as shown in Figure 1 terminates in a cylinder 90 after passing through a check valve 92. Each cylinder 90 (one for each rotor R) is part of an air compressor unit having a piston 94 operated by a connecting rod 96 from the cam shaft 32. The cam shaft 32 has a crank pin 98 for the connecting rod.

The air compressor unit 90—94 has inlet ports 100 communicating with a compressed air manifold 102 into which air is introduced at, for instance, 250 pounds pressure. A cylindrical shutter 104 is provided for controlling the air supply into the manifold and the shutter in turn is connected with a control link 106 by means of a pin 108 or other suitable connecting means (see Figure 3). The pin 108 passes through an arcuate slot 109 in the manifold and a flange 103 around the shutter 104 seals the slot under pressure of the air within the manifold. Adjacent the center

of the engine, an outlet valve 110 is provided for the air compressor 90—94 and is surrounded by an annulus 112.

A fuel control unit is provided consisting of an air outlet valve 114, fuel inlet valve 116, and an air inlet valve 118. The three valves just mentioned are located in cylinders 115, 117 and 119 respectively. The valves 114, 116 and 118 open into a bore 120 having an insert 122 retained therein by a plug 124. A passageway 126 leads from the bore 120 through a check valve 128 into the annulus 112.

The valves 114, 116 and 118 are adapted to be opened in the order named by cam-lobes 130, 132 and 134 on a cam 136. The cam 136 is mounted on the cam shaft 32. The cam lobe 130 is adapted to engage a head 131 of the valve 114 to effect its opening. Similarly the lobes 132 and 134 are adapted to engage heads 133 and 135 of the valves 116 and 118. The valves 116 and 118 may be adjusted as to degree of opening by means of the control link 106. It is operatively connected to the heads 133 and 135 by oscillatable bands 138 pivoted thereto as at 140 and connected with the stems of the valves by pins 142 extending through slots in the cylinders 117 and 119.

Associated with the stems of the valves 116 and 118 are seal-off diaphragms 144, and fuel, for instance under 100 pounds pressure, is introduced at 146 into the valve 116 whereas compressed air at considerably higher pressure, for instance 3000 pounds per square inch, is introduced at 148 to the valve 118.

Operating in conjunction with the fuel control unit and the air compressor unit, I provide an explosion control unit which will now be described. The explosion control unit comprises a first piston P¹ and a second piston P² telescopically related to each other as shown in Figure 3A, the piston P¹ operating in a pair of bores 150 and 152 of the stator head 125. The piston P¹ is tubular so as at times to fit around the annulus 112 and is driven by explosion as will hereinafter appear. Locking means is provided for the piston P¹ comprising an auxiliary crank shaft 154 journaled in a sleeve 156 passing through a tube 158. The tube 158 is part of the frame F and compressed air is supplied thereto from a pipe 160, such air being at about 250 pounds per square inch.

The auxiliary crank shaft 154 has crank arms 162 thereon connected by links 163 with a sleeve 164 surrounding the piston P¹. The sleeve 164 has limited longitudinal motion on the piston between an annular flange 166 thereon and a ring 168. A spring 170 biases the sleeve 164 toward the ring 168.

The piston P² slides inside the piston P¹ and outside the tube 158. A valve 172 is located between the piston P² and the tube 158, seating at times on a seat 174 of the tube. The valve is biased toward seating position by a spring 176 and has a head 178 that permits the piston P² when it moves toward the left to unseat the valve.

The joint between the crank arms 162 and the links 163 are provided with extension pins 180 (see Figure 1A) which are adapted to be alternately engaged by cam lobes 182 and 184 carried by discs 186 mounted on the crank shaft 36. The lobes 182 and 184 effect an unlocking and a locking action respectively of the arms 162 and the links 163 in, or slightly past, dead center position as will be described later in the operation of my engine.

For oiling the engine, a lubricating oil reservoir 188 is provided from which an intake pipe 190 extends to passageways 192 and 194 and through a check valve 196 into a cavity C formed between the first piston P¹ and the second piston P². Leading from this cavity is a check valve 198 and passages 200 and 202 returning to the reservoir 188. The piston P² is suitably connected to a ring 158a of the tube 158 to prevent relative rotation so that the passageways 192 and 194, and the passageways 200 and 202 may align with each other at certain points in the operating cycle of the elements, thereby metering the oil into and out of the cavity C and oiling the pistons P¹ and P² and the tube 158.

A further oiling means is provided as shown in Figure 1A consisting of an intake tube 204 leading from the sump formed in the frame F, through a check valve 206 to a cavity C¹ formed between the piston P¹ and the stator head 125. Leading from this cavity is a check valve 208 and a spray nozzle 210 from which oil is sprayed onto the working parts of the engine. The engine is preferably provided with a cover (not shown) coacting with the frame F to completely enclose the working parts in an oil tight manner.

Although in some instances I have described only one rotor, fuel control unit or explosion control unit, it is to be understood that two complete units are provided as shown on the drawings and more units may be added if desirable. The two rotors are arranged with their notches diametrically opposite each other so that while one rotor is on the power stroke the other is on the exhaust stroke, and vice-versa. The various operating units are properly timed to secure the cycle of operations described under "Practical operation."

The fuel to the engine may be supplied by means of a pump, and the air at two different pressures by means of a pair of compressors which are connected with the main shaft 18. Since mechanism of this character is conventional I have made no attempt to show it on the drawings.

Practical operation

In the operation of my engine, assuming the rotor to be in the position shown in Figures 3 and 3A, about ready for the explosion to occur, there is a relatively high pressure within the piston P¹ between the valve 110 and the head of the piston P². This may be in the neighborhood of 500 pounds per square inch, and therefore opposes the 250 pounds per square inch entering from the pipe 160 through the valve 172. The valve, therefore, is closed and the pressure inside the piston P² and to the left of the valve may be about 250 pounds due to the area of the left end of the tube 158 being about twice the area of the piston P² at its left end. At this time, the piston P¹ is locked in position with its left end surrounding the annulus 112 by the crank arms 162 and the links 163 being at or slightly past dead center position.

Fuel and air under high pressure are now injected or sprayed from the passageway 126 into the cavity indicated as C², and due to the temperature of the compressed air the fuel explodes without the necessity of a spark plug. Substantially simultaneously with the introduction of the fuel, the discs 186 have rotated to a position for the cam-lobes 182 to strike the projections 180 and thereby unlock the arms 162 and links 163 from dead center position so that when explosion

does occur, it can drive the piston P¹ toward the right to the position of Figure 7. This opens the cavity C² and permits the exploded charge to enter the stator and the notch of the rotor, thereby acting on the face of the abutment bar 44 and the face 12 of the rotor (adjacent each other in Figure 3A) causing the rotor to be driven clockwise due to the expansion of the gases of explosion, the chamber C² between the abutment bar and the notch face 12 expanding due to such rotation. Since the notch faces 12 and 14 are at an angle as shown in Figures 9 and 10, openings 15 are provided from their faces to the outer faces of the rotors to relieve side pressure and therefore friction occurring at this point.

When the piston P¹ is crowded against the annulus 112 by the lobes 184 on the disks 186 coming in contact with the projections 180 and crowding the arms 162 and the links 163 to dead center position, the springs 170 are then under some compression and their pressure causes such crowding of the piston P¹ against the annulus. The arms and links being directly connected to the sleeve 164 through the pins 165 cause this crowding action, as shown in the bottom half of Figure 1A and in Figure 3A. It will be noted that the sleeve 164 is slightly spaced from the ring 168 at that time. This holds the piston P¹ in position while the cavity C² is being filled with air from the cylinder 90 when the piston 94 has completed its stroke for delivering the air into the cavity. By this time the disks 186 have brought the lobes 182 in contact with the projections 180 for releasing the arms and links from dead center position substantially simultaneously with the explosion in the cavity C². The arms 162 and the links 163 do not pull the piston P¹ from the annulus 112, however, as if there is no explosion in the cavity C² then the slack is taken up between the sleeve 164 and the ring 168, and the piston P¹ is positively pulled loose from the annulus 112. When this takes place the compressed air in cavity C² acts on the piston P¹ the same as a light explosion, freeing the opening between the cavity and the expansion chamber of the rotor so that such air from the cavity C² is released in the expansion chamber. During these operations the spring 170 introduces an interval of time between the release of the arms 162 and the links 163 from the dead center position and the beginning of the positive pulling of the piston P¹ toward the right. If there is an explosion in the cavity C², as there should be, then the expanding gases are released from the cavity by the piston P¹ leaving the annulus 112 so that these expanding gases are transformed into work by acting in the expandable chamber of the rotor. The piston P¹ thus acts as an explosion control, opening the cavity C² to the rotor so that the expanding gases from the cavity can act on the rotor.

When the parts are in the position of Figure 7 and just after the explosion has taken place, the rotor is then at the position shown diagrammatically in Figure 4 and moves on as to the position shown in Figure 5. This permits the pressure of the exploded gases to reduce as they expand and effects a reduction of the pressure on the left end of the piston P² so that finally the 250 pounds pressure under the valve 172 opens it and drives the piston P² toward the left. The final reduction of pressure in the stator is effected by the movement of the rotor to the position of Figure 6 where the notch edge 12 uncovers initial exhaust ports 17. This still leaves a pocket of spent gases in the notch, and accordingly when

the notch end 12 reaches other exhaust ports 19, which may be called the "main" exhaust ports, the notch is opened to atmosphere therethrough. After the notch end 12 passes the abutment bar 44, the bar is moved into the notch so that there is provided a contracting cavity shown at C³ in Figure 4 and further contracted at C⁴ in Figure 5. The contracting cavity scavenges the last of the spent gases from the notch in the rotor through the main exhaust ports.

During the cycle of operations of the explosion control unit as just described, the fuel control and air compressor units operate as follows: When the rotor is about in the position of Figure 6, the piston 94 is at the outer end of its stroke as shown in Figure 3. Accordingly air is being admitted at 250 pounds pressure from the manifold 102 through the ports 100 and into the cylinder 90. As the piston travels forward it cuts off the ports 100 and compresses the air, forcing the air through the valve 110 when its pressure is sufficient to overcome the air pressure on the end of the piston P².

Adjacent the end of the compression stroke, the cam lobe 130 opens the air outlet valve 114 for exhausting the space adjacent the insert 122, permitting the air therein to pass to atmosphere along the valve stem in the cylinder 115 and finally through outlet ports 115^a (see Figure 1). The cam lobe 132 then opens the fuel inlet valve 116 to permit a predetermined quantity of fuel to be injected as determined by the setting of the link 106, the air to the cylinder 90 having also been adjusted by the same link. After the fuel valve 116 closes, the cam lobe 134 opens the air inlet valve 118 to admit air at 3000 pounds pressure which sprays the oil from the passageway 26, forcing it through the check valve 128. The oil being sprayed into the relatively hot compressed air in the cavity C², causes an explosion, thus completing operation of the explosion control unit as already described.

The air passing through valve 118 does not ignite the fuel before passing through the check valve 128 because the fuel entering the space adjacent the insert 122 when the space has an atmospheric pressure is a mixture which is too rich to explode.

As to the valve 114, its purpose is to exhaust the small space in the bore 120 adjacent the insert 122 so it will be at atmospheric pressure before being raised to the pressure of cavity C² when the piston P¹ closes around the annulus 112. If the fuel were forced into the bore 120 at a high enough pressure without the bore being exhausted by the opening of the valve 114, there might be a premature explosion.

During a cycle of operation, the shuttle valve operates as follows: Referring to Figure 9, the abutment bar 44 has just been moved in an upward direction relative to the drawings by the compressed air in the upper cylinder 48 that was compressed therein by the upper power piston P¹. The exhaust port 88 is controlled by the check valve 92 (see Figure 1), so that whenever the pressure in the cylinder 90 is less than the pressure in the cylinder 48, air will be exhausted through the valve to permit the upper piston P to return later in the downward direction of Figure 9. The piston 94 when traveling to the left (Figure 1) permits such exhaust of air from the piston 48 and the air and its pressure are therefore utilized in the cylinder 90 instead of being wasted to atmosphere.

When the rotor R rotates about a half revo-

lution and the notch end 14 in Figure 10 engages the abutment bar 44, the lower power piston P¹ will have traveled forward in its cylinder after picking up air at 250 pounds pressure from its inlet port 58 and compresses it behind the lower shuttle valve piston P. Thereupon the right hand arm 86 on the main shaft 18 (see Figure 8) will engage the right-hand trigger 74 for moving it against the action of its spring 84 thereby breaking the right hand joint 70 so that the abutment bar is unlocked and can travel downwardly in Figure 10 due to the compressed air behind the lower piston P of Figure 9.

The abutment bar, in thus traveling downwardly, follows the notch end 12 of the lower rotor R and the lower notch 14 of the upper rotor follows the abutment bar as appears from an inspection of Figure 10. When the other half revolution takes place, the operation is reversed so that the abutment bar then moves upwardly again at the proper time to the position of Figure 9, thus forming at all times an abutment between the ends of the notches in the rotor so that ahead of the abutment there is an expansible chamber for the power stroke, and behind the abutment a contracting chamber for the exhaust stroke.

From the foregoing specification it is believed obvious that I have provided a rotor arrangement that produces in conjunction with a properly moving abutment bar, a means to utilize the force of exploded fuel to effect rotation of a power shaft. The rotor is fed with fuel from the fuel control unit which may be readily adjusted for all speeds of operation. The shuttle valve is controlled by compressed air which in turn is properly controlled so as to effect the movement of the abutment bar in a positive manner and at the proper time.

The double piston arrangement of the explosion control unit confines the charge of compressed air and fuel until such time as the explosion takes place and it is then released into the expansible chamber of the rotor to effect power application thereto. When the exploded gas is spent, the explosion control unit is operated by compressed air and locked in position by rotation of the engine for a subsequent explosion control function. The various functions of the different units are performed in the proper sequence and at the proper time in an operating cycle to produce an efficiently operable engine of the internal combustion type.

Provision has been made for oiling the various working parts of the engine by utilizing certain cavities in the explosion control unit which alternately expand and contract, suitable passageways and check valves being provided to control the oil flow. Some parts of the engine shown integral on the drawings, such as the cylinders 48 and 158, would be separately formed and attached to the frame F for convenience in assembly. I have made no attempt to go into detail as to the exact construction, except to show broadly the general organization of parts.

Some changes may be made in the construction and arrangement of the parts of my device without departing from the real spirit and purpose of my invention, and it is my intention to cover by my claims any modified forms of structure or use of mechanical equivalents, which may be reasonably included within their scope without sacrificing any of the advantages thereof.

I claim as my invention:

1. In an internal combustion engine, a stator, 75 a rotor therein having a notch, a shuttle valve

movable into said notch to form an expansion chamber in conjunction with one end of said notch, means for moving said shuttle valve in timed relation to said rotor comprising a shuttle valve cylinder, a shuttle valve piston therein, a power cylinder, a power piston in said power cylinder driven by said rotor, means for locking said shuttle valve against movement comprising a check arm and a link having a dead center position, means actuated by said rotor for breaking the check arm and link from dead center position after the compressed air in said power cylinder has been introduced into said shuttle valve cylinder, a chamber, and means for introducing an explosive fuel mixture into said last chamber, exploding the same and introducing the resulting gases into said expansible chamber.

2. In an internal combustion engine, a stator, a rotor therein having a notch, a shuttle valve movable into said notch to form an expansible chamber in conjunction with one end of said notch, means for moving said shuttle valve comprising a cylinder, a shuttle valve piston therein, a power cylinder, means for supplying compressed air thereto, a power piston in said power cylinder driven by said rotor, means for locking said shuttle valve against movement comprising a check arm and a link having a dead center position, means actuated by said rotor for breaking the check arm and link from dead center position when the air in said power cylinder is further compressed, and after it has been introduced into said shuttle valve cylinder, a fuel control unit receiving exhaust air from said shuttle valve cylinder, a chamber, said fuel control unit introducing an explosive fuel mixture into said last chamber, exploding the same and introducing the resulting gases into said expansible chamber.

3. In an internal combustion engine, a stator, a rotor therein having a notch, a shuttle valve movable into said notch to form an expansible chamber in conjunction with one end of said notch, means for moving said shuttle valve in timed relation to said rotor, means for compressing air and discharging it into said expansible chamber, an explosion control chamber, and means for introducing an explosive fuel mixture into said explosion control chamber and therefrom to said expansible chamber and exploding the same, said last means including a fuel control unit receiving fuel under pressure and then air under pressure, the air effecting spraying of the fuel into said explosion control chamber and into the air compressed therein, exploding the same and introducing the resulting mixture into said expansible chamber.

4. In an internal combustion engine, a stator, a notched rotor therein, a shuttle valve movable into the notch of said rotor to form expansible and contractible chambers therein, means for moving said shuttle valve in timed relation to said rotor, a chamber, means for introducing an explosive fuel mixture into said last chamber, exploding the same and introducing the resulting gases into said expansible and contractible chambers, and means for exhausting the exploded gases from said notch, said last means including initial and main exhaust ports in said stator and controlled by the ends of said notch in their movement past said ports.

5. In an internal combustion engine, a stator, a rotor therein having a notch, a shuttle valve movable into said notch to form an expansion chamber in conjunction with one end of said notch, means for moving said shuttle valve in

timed relation to said rotor, an explosion chamber, a fuel control unit for said rotor comprising an air outlet valve, a fuel inlet valve, and an air inlet valve operable successively to exhaust air from the unit, introduce fuel thereto and air at high pressure to said explosion control chamber to form a combustible mixture, explode the same and introducing the resulting gases into said expansion chamber, and an air compressor unit operating in conjunction with said fuel control unit and receiving compressed air and compressing it to a higher pressure and discharging it into said expansible chamber with the air and fuel from said fuel control unit.

15 6. In an internal combustion engine, a stator, a rotor therein having a notch, a shuttle valve movable into said notch to form an expansion chamber in conjunction with one end of said notch means for moving said shuttle valve in timed relation to said rotor, a chamber, a fuel control unit for said rotor comprising an air outlet valve, a fuel inlet valve, and an air inlet valve operable successively to exhaust air from the unit, introduce fuel thereto and air at high pressure to said last chamber to form a combustible mixture, explode the same and introducing the resulting gases into said expansible chamber.

20 7. In an internal combustion engine, a stator, a rotor therein having a notch, a shuttle valve movable into said notch to form an expansible chamber in conjunction with one end of said notch, means for moving said shuttle valve in timed relation to said rotor, an explosion chamber, a fuel control unit for said rotor for introducing a combustible mixture to said explosion chamber, explode the same and introducing the resulting gases into said expansible chamber, and an air compressor unit operating in conjunction with said fuel control unit to discharge air into said expansible chamber prior to the fuel from said fuel control unit being discharged thereinto.

25 8. In an internal combustion engine, a stator, a rotor therein having a notch, a shuttle valve movable into said notch to form an expansible chamber in conjunction with one end of said notch, means for moving said shuttle valve in timed relation to said rotor, an explosion control unit for said rotor comprising a first piston and a second piston telescopically related to each other, check arm and link means for locking said first piston in one position and permitting the second piston to be telescoped therein by build-up of pressure therein when the check arm and link means is in a dead center position, an air compressor unit for effecting such build-up of pressure, means for introducing compressed air on the opposite side of said second piston in opposition to such build-up of pressure by said air compressor, a valve for closing communication between said second piston and said last source of compressed air until the build-up of pressure exceeds the pressure of the compressed air, means for unlocking said check arm and link means from dead center position whereby said first piston may be moved by the pressure built up thereagainst when fuel is introduced into said expansion chamber and exploded, said last compressed air effecting return of said first and second pistons to initial position after the explosion takes place and pressure in the expansible chamber is reduced by exhaust therefrom, and means driven by said rotor for moving said check arm and link means to and from dead center position.

30 9. An internal combustion engine comprising a

stator, a rotor therein having a notch, a shuttle valve movable into said notch to form an expansible chamber in conjunction with one end of said notch, means for moving said shuttle valve in timed relation to said rotor, an explosion control unit for said rotor comprising a first piston and a second piston telescopically related to each other, means for locking said first piston in one position and permitting the second piston to be telescoped therein by build-up of pressure therein means for introducing compressed air on the opposite side of said second piston in opposition to such build-up of pressure a valve for closing communication between said second piston and said last source of compressed air until the build-up of pressure exceeds the pressure of the compressed air, and means for unlocking said first piston when the pressure is built up and fuel is introduced into said expansible chamber and exploded, said last compressed air effecting return of said first and second pistons to initial position after the explosion takes place and pressure in the expansible chamber is reduced by exhaust therefrom.

10. In an internal combustion engine, a stator, a rotor therein having a notch, a shuttle valve movable into said notch to form an expansible chamber therein, means for moving said shuttle valve in timed relation to said rotor, an explosion control unit for said rotor comprising a first piston and a second piston telescopically related, means for locking said first piston in one position and permitting the second piston to be telescoped by build-up of pressure in said expansible chamber, means for introducing compressed air on the opposite side of said second piston in opposition to such build-up of pressure means for closing communication between said second piston and said last source of compressed air until the build up of pressure exceeds the pressure of the compressed air, and means for unlocking said first piston when the pressure is built up and fuel is introduced into said expansion chamber and exploded.

11. In an internal combustion engine, a stator, a rotor therein having a notch, a shuttle valve movable into said notch to form an expansible chamber in conjunction with one end of said notch, compressed air means for moving said shuttle valve in timed relation to said rotor, a fuel control unit for said rotor comprising an air outlet valve, a fuel inlet valve, and an air inlet valve operable successively to exhaust air from the unit, and introduce fuel and then air at high pressure to said expansible chamber to form a combustible mixture and explode the same therein, an air compressor unit operating in conjunction with said fuel control unit and receiving compressed air and compressing it to a higher pressure and discharging it into said expansible chamber with the air and fuel from said fuel control unit, an explosion control unit for said rotor comprising a first piston and a second piston telescopically related to each other, means for locking said first piston in one position and permitting the second piston to be telescoped therein by build-up of pressure therein by said air compressor unit, means for introducing compressed air on the opposite side of said second piston in opposition to such build-up of pressure by said air compressor, a valve for closing communication between said second piston and said last source of compressed air until the build-up of pressure exceeds the pressure of the compressed air, means for unlocking said first piston when the pressure is built up

5 and fuel is introduced into said expansion chamber and exploded, said last compressed air effecting return of said first and second pistons to initial position after the explosion takes place and pressure in the expansible chamber is reduced by exhaust therefrom.

12. In an internal combustion engine, a stator, a rotor therein having a notch, a shuttle valve movable into said notch to form an expansible chamber in conjunction with one end of said notch, means for moving said shuttle valve in timed relation to said rotor, a fuel control unit for said rotor comprising an air outlet valve, a fuel inlet valve, and an air inlet valve operable successively to exhaust air from the unit, and introduce fuel and then air at high pressure to said expansible chamber to form a combustible mixture and explode the same therein, an explosion control unit for said rotor comprising a first piston and a second piston telescopically related to each other, means for locking said first piston in one position and permitting the second piston to be telescoped therein by build-up of pressure therein, means for introducing compressed air on the opposite side of said second piston in opposition to such build-up of pressure, a valve for closing communication between said second piston and said last source of compressed air until the build-up of pressure exceeds the pressure of the compressed air, means for unlocking said first piston when the pressure is built up and fuel is introduced into said expansion chamber and exploded, said last compressed air effecting return of said first and second pistons to initial position after the explosion takes place the pressure in the expansible chamber is reduced by exhaust therefrom.

13. In an internal combustion engine, a stator, a rotor therein having a notch, a shuttle valve movable into said notch to form an expansible chamber in conjunction with one end of the notch, means for moving said shuttle valve in timed relation to said rotor, a fuel control unit for said rotor comprising a fuel inlet valve and an air inlet valve operable successively to introduce fuel and then air at high pressure to said expansible chamber to form a combustible mixture therein and to explode the same, and an air compressor unit operating in conjunction with said fuel control unit and discharging compressed air into said expansible chamber with the air and fuel from said fuel control unit, an explosion control unit for said rotor comprising a first piston and a second piston telescopically related to each other, means for locking said first piston in one position and permitting the second piston to be telescoped therein by build-up of pressure in said expansible chamber, means for introducing compressed air on the opposite side of said second piston in opposition to such build-up of pressure, a valve for closing communication between said second piston and said last source of compressed air until the build-up of pressure exceeds the pressure of the compressed air, and means for unlocking said first piston when the pressure is built up and fuel is introduced into said expansion chamber and exploded.

14. In an internal combustion engine, a stator, a rotor therein having a notch, a shuttle valve movable into said notch to form an expansible chamber in conjunction with one end of the notch, means for moving said shuttle valve in timed relation to said rotor, a fuel control unit for said rotor, an air compressor unit operating in conjunction therewith, an explosion control unit

for said rotor comprising a first piston and a second piston telescopically related to each other, and a valve for closing communication between said second piston and a source of compressed air thereto until build-up of pressure exceeds the pressure of the compressed air, said last compressed air effecting return of said first and second pistons to initial position after the explosion, expansion and exhaust take place.

15. In an internal combustion engine, a stator, a rotor therein having a notch, a shuttle valve movable into said notch, means for moving said shuttle valve in timed relation to said rotor, an explosion control unit for said rotor comprising a first piston and a second piston telescopically related to each other, means for locking said first piston in one position and permitting the second piston to be telescoped therein by build-up of

pressure therein, an air compressor unit for effecting such build-up of pressure, means for introducing compressed air on the opposite side of said second piston in opposition to such build-up of pressure by said air compressor unit, means for closing communication between said second piston and said last source of compressed air until the build-up of pressure exceeds the pressure of the compressed air, means for unlocking said first piston when the pressure is built up and fuel is introduced into said stator and exploded, said last compressed air effecting return of said first and second pistons to initial position after the explosion takes place and pressure in the expandible chamber is reduced by exhaust therefrom, and means driven by said rotor for operating said locking means.

CHARLES I. FOX.
